(57) **CLAIM**

The ornamental design for a seatbelt shoulder pad, as shown and described in the preceding Figures.

DESCRIPTION

FIG. 1 is a perspective view of a seatbelt shoulder pad on a seatbelt;

FIG. 2 is a perspective side view of a seatbelt shoulder pad; and,

FIG. 3 is an end view of a seatbelt shoulder pad.

The broken lines are included for the purpose of illustrating environmental features and form no part of the claimed design.
